SHOCKPROOF OR CUSHIONED CARTON

Aaron Grossman and Felix Transport, New York, N.Y.,
assignors to Domrico Inc., New York, N.Y., a corpora-
tion of New York

Filed Nov. 7, 1961, Ser. No. 150,747
9 Claims. (Cl. 229—14)

This invention relates to improvements in cartons and is directed particularly to the provision of an improved shockproof or cushioned carton or receptacle designed for merchandising fragile articles such as bottles and the like.

In the packaging of many articles for display and sale, particularly in connection with the merchandising of toiletries, the merchandise is generally displayed and sold in the carton or receptacle in which it is put up for shipment.

Such merchandise is usually contained in bottles or other fragile containers. Accordingly, the provision of a shockproof or cushioned carton is desirable.

It is also the practice to merchandise many articles, particularly toiletries, in cartons or receptacles made of relatively expensive foil or foil covered sheet material to enhance the attractiveness of the carton in which the container of the merchandise is sold.

In the light of the foregoing, it is a particular object of the present invention to provide a new shockproof or cushioned carton or receptacle embodying spaced inner and outer shell parts joined together in a novel manner and in cushioned relation one with the other, wherein the inner part may be made of relatively inexpensive material and the outer part made of a better grade and attractive and more expensive material, such as foil or the like.

It is another object of the invention to provide a two part blank for the formation of a shockproof or cushioned carton or receptacle whereby one part of the blank may be formed of a different material from the other part and wherein the two parts of the blank are coupled together in a novel manner to form a unitary structure which can be folded in such a way as to provide an inner tubular shell and an outer tubular shell with spacing elements between the shells.

It is another object of the invention to provide a novel two part blank for the formation of a cushioned receptacle consisting of an inner shell and outer shell and wherein the blank part for the formation of the inner shell is so designed that when the two part blank is folded to form the completed carton, the top of the inner shell will lie below the top of the outer shell, thereby providing a clearance to facilitate grasping the top of a container such as a bottle or the like, for easy removal of the latter from the carton.

Other objects and advantages of the invention will become apparent as the description of the same proceeds and the invention will be best understood from a consideration of the following detailed description taken in connection with the accompanying drawings, wherein:

FIG. 1 is a flat view of the two parts of the carton blank illustrating the same spaced apart at the ends thereof which are designed to be coupled together.

FIG. 2 is a flat view of the blank with the two parts interlocked or coupled together and showing the blank turned over from right to left.

FIG. 3 is a perspective view of the carton or container folded in the body portion thereof but with the top and bottom closure flaps in opened position.

FIG. 4 is a view looking into the open top of the carton or container and showing the bottom closure flaps in folded position.

FIG. 5 illustrates the form which the inner tubular shell portion of the carton takes when the blank is folded to

2

form the complete carton, this view showing particularly the locking panel section forming a part of the inner shell.

FIG. 6 is a sectional view taken in a vertical plane substantially on the line 6—6 of FIG. 4.

FIG. 7 is a longitudinal section taken in a vertical plane substantially on the line 7—7 of FIG. 4.

Referring now more particularly to the drawings, the numeral 10 generally designates the complete two part blank from which the two shell portions, sections or units are produced when the blank is folded.

The blank comprises the outer part 12 and inner part 14 which produce, when coupled together and folded, the hereinafter referred to outer tubular shell and inner tubular shell, respectively.

The outer part 12 of the blank comprises the four substantially rectangular panels 16, 18, 20 and 22, which are disposed in aligned relation or series and are separated by the parallel fold lines 24, 26 and 28.

The panel 22 is joined by the fold line 30 to an intermediate half panel 32.

The inner part 14 of the two part blank comprises the five substantially rectangular panels 34, 36, 38, 40 and 42 which are connected together along the fold lines 44, 46 and 50.

The panel 34 of the blank inner part 14 is connected joined along the fold or score line 52 to a half panel 54.

The blank inner part 14 has the straight top and bottom edges 56 and 58, respectively, thus making all of the panels 34 to 42 of the same height. However, the half panel 54 has the bottom edge thereof in line with the bottom edge 58 of the adjacent panels, as indicated at 60, but this half panel 54 extends beyond or above the edge 56 and it will be seen that the half panel 54 is of the same height as the half panel 32, to which it is coupled to form the formation of the complete blank in the manner hereafter described.

The blank outer part 12 includes the bottom flaps 62, 64 and 66 which are joined respectively by the fold score lines 68, 70 and 72 to the bottom ends of the panels 16, 18 and 22. Also, the bottom cover flap 62 is provided with a transverse fold score line 74 and is disposed at the ends of the score line for effecting the interlocking of the bottom cover flap 62 with the flaps 64 and 66 when they are folded one over the other.

The top ends of the panels 18, 20 and 22 are joined to flaps 78, 80 and 82, respectively, by the fold score lines 84, 86 and 88, respectively. Also, the flap 82, which is the cover flap to overlie the flaps 78 and 80 when they are folded, is joined by a fold score line 90 to a tuck-in tongue 92.

As will be seen, the fold score line 74 across the bottom cover flap 62 separates the flap proper from the tuck-in tongue 94.

The fold score lines 44 to 50, inclusive, are interrupted by cuts *a* of substantially U-shaped outline. These cuts define, along each score line, alternate opposite directed tabs 95 and 96.

The half panels 32 and 54, when coupled together in a manner about to be described, form a complete intermediate panel which is generally designated 98, between the inner and outer parts 12 and 14 to form a complete blank structure.

The coupling together of the half panels 32 and 54 so that the complete intermediate panel 98 will be substantially flat, is effected in the following manner.

One of the half panels, here shown as the half panel 32, has the vertical side edge or free vertical edge 1 thereof cut away or cut out intermediate its ends to form the recess 101. The inner edge of this recess is extended upwardly as a slit, as indicated at 102, to form the tongue 103.

The bottom edge of the half panel 32 is provided with a short upwardly extending slit 104, thereby providing the downwardly directed tongue 105.

The vertical free edge portion of the half panel 34 is likewise cut out intermediate its ends forming the recess 106. The edge of this recess is extended into the slit 107 in the lower part or at the lower end thereof, forming the upwardly directed locking tongue 103. At the upper end of the recess 106, an upwardly directed locking tongue 109 is formed by cutting the material of the half flap 54, downwardly from the top edge to form the slit 110.

It will be noted that the slits 102 and 104 in the half panel 32 are in alignment vertically of the half panel and also the slits 107 and 110 in the half panel 34 are in alignment.

The two parts 12 and 14 of the blank are interlocked to form the complete intermediate panel 98 by crossing the two half panels so as to bring the slits 102 and 104 respectively in alignment with the slits 110 and 107 and then by relatively moving the two half panels in opposite directions, the adjacent slits of the two half panels will be caused to receive the adjacent portions of the two panels which lie at the ends of the crossed tongues, thereby interlocking the half panels in the manner illustrated in FIG. 2. When this is accomplished, it will be seen that the two tongues of one half panel will lie against a face of the other half panel.

It will also be seen upon reference to FIG. 2, where the two parts of the blank are shown thus coupled together, that the intermediate panel 98 is of the same height as the panels of the outer part of the blank and also it will be seen that the bottom line of the intermediate panel will be in the same line as the bottom edge 58 of the inner part and the bottom lines of the panels 16 to 22 of the outer part.

FIG. 1 of the drawing shows the outer sides or outer surfaces of the two parts of the blank, whereas FIG. 2 shows the inner surfaces thereof. The operation of folding the two part blank will thus be described in connection with the showing of FIG. 2.

In folding the two part blank after the parts have been coupled together as described, to form the shock-proof or cushioned carton, the panels 36 to 42 are folded along the fold score lines 44 to 50 so as to bring the terminal panel 42 to position against the inner face of the panel 34. The panels will accordingly lie in the relationship in which they are shown in FIG. 5 to form the inner tubular shell of the carton, which is generally designated I.

In this folding operation of the inner part 14, the tabs *a* will be broken out and will project outwardly from the corners of the shell in four directions to function as spacers between the inner shell and the outer shell.

The two part intermediate panel is then folded over the outer side of panel 40, the fold being made along the crease line 52, which crease line is interrupted by straight, short slits 52' to facilitate the formation of a sharp bend in the material.

Also, it is to be noted that the panel 34 is of slightly greater width than the panels 36 to 40 whereby, as shown in FIG. 5, the spacer tabs *a* along the fold line 50 will hold off the intermediate panel from the panel 40 a distance equal to the extent of outward projection of the tabs.

The panels 16 to 22 are then folded around the inner tubular shell, being folded along the fold crease lines 24, 26, 28 and 30, thereby bringing the terminal panel 16 into position against the outer side of the two part intermediate panel 98 and to which the terminal panel 16 will be secured by the application of its suitable adhesive, not shown, to its inner surface. Thus, there will be formed the outer tubular shell which is generally designated O, which

encircles the inner tubular shell I as most clearly seen in FIGS. 4, 6 and 7.

Since the panels 16 to 22 of the outer part 12 of the blank are wider than the panels of the inner part, the two shells will be spaced apart from one another and this spacing will be maintained against the collapse by the outwardly projecting corner spacer tabs *a* as clearly illustrated in the figures referred to.

When the bottom flaps 64 and 66 of the carton are brought into overlapping relation, the closure flap 62 is then folded in against the flaps 64 and 66 and the tuck in tongue 94 is inserted in the conventional manner and the slits will receive adjacent corner portions of the flaps 64 and 66 to form a locking connection with the same, this action being facilitated by the slight recessing of the adjacent edges of the flaps 64 and 66 as indicated at 64'-66'.

It will be readily apparent from the foregoing that the blank for the formation of a shockproof or cushioned carton in accordance with the present invention can not only be readily cut or stamped from the desired sheet material on existing automatic machinery, but also, by providing the blank and two readily joined or coupled together parts, the carton to be formed therefrom may have the inner tubular shell part constructed of a relatively inexpensive material while the outer shell part can be made or constructed from a more expensive material of desired attractive appearance to make the carton or receptacle suitable for use in the merchandising of cosmetics or other merchandise where it is desirable to have the receptacle of attractive appearance.

The present invention accordingly makes it possible to produce receptacles of the nature described at considerably less expense while using a relatively expensive foil or other attractive material for the exterior part thereof, than would be possible if the carton blank were formed in a single piece which would necessitate placing the covering of a portion of such expensive material in a part of the carton structure which, by means of the present invention, can be made of relatively cheap material.

It will also be noted that in the present carton or receptacle structure, a novel feature resides in the formation of the inner shell so that the top part thereof will lie below the top of the outer shell. Thus, when a bottle or other container such as that illustrated in broken lines and designated C, is placed within the inner shell, the head or neck portion C' will project above the top of the inner shell and there is ample space therearound for the introduction of the fingers to grasp the top of the container so that it may be easily removed.

As this invention may be embodied in several forms without departing from the spirit or essential characteristics thereof, the present embodiment is therefore illustrative and not restrictive, since the scope of the invention is defined in the appended claims, and all changes that fall within the metes and bounds of the claims, or that form their functional as well as conjointly cooperative equivalents, are therefore intended to be embraced by those claims.

We claim:

1. A shockproof receptacle comprising an outer tubular shell having a top and a bottom end, bottom and closure flaps therefor, top end closure flaps therefor, an inner tubular shell of materially smaller cross-sectional dimensions than the outer shell and enclosed in the outer shell, means between the shells for maintaining the same in spaced relation, the inner shell having open top and bottom ends, the said outer shell being formed of a material of different character and different commercial value from the material of the inner shell, and the inner and outer shells each having a longitudinally extending portion of a wall joined to the corresponding wall portion of the other shell and forming an intermediate two-part wall between the shells which two parts of the intermediate wall holds the two shells of the said materials of different character against relative longitudinal movement.

2. A shockproof receptacle structure according to claim 1, wherein the inner shell is of materially less length than the outer shell and terminates at its top end a substantial distance below the top end of the outer shell, while the bottom end of the inner shell lies closely adjacent to the bottom end closure flaps when the latter are in closed position.

3. A cushion receptacle comprising two tubular shells having top and bottom ends and each of substantially quadrangular cross-section and positioned one within the other, the inner shell being of materially smaller size than the outer shell, means carried by one of the shells between the walls of the shells for maintaining the shells in spaced relation, each shell having a fifth wall of approximately half the width of its other walls, means joining together the fifth walls of the two shells in partially overlapped parallel relation whereby the two joined half-width walls form an intermediate connecting wall between the shells, the said intermediate connecting wall being maintained in spaced relation with a wall of the inner shell by certain of the first stated means, the said intermediate wall being secured on the outer side surface thereof to the inner side surface of an overlying wall of the outer shell, and closure means for the ends of the outer shell.

4. A receptacle according to claim 3, wherein the two shells are formed of at least two materials of different characteristics.

5. The invention according to claim 3, wherein the inner shell is of materially less length than the outer shell and terminates at its top end a substantial distance below the top end of the outer shell and has an unobstructed open top to thereby provide finger space for facilitating the grasping of the top end of a container located in the inner shell.

6. The invention according to claim 3, wherein the said half-width fifth walls of the shells are both of substantially the same vertical length as the walls of the outer shell and the other walls of the inner shell terminate at their top ends a substantial distance below the top ends of the walls of the outer shell and of the two half-width fifth walls and terminate at their bottom ends in approximately the same plane transversely of the receptacle as the bottom ends of the walls of the outer shell and the half-width fifth walls.

7. The invention according to claim 3, wherein the said means joining together the said half-width fifth walls of the two shells comprises interlocking tongues frictionally maintained in substantially parallel interlocking engagement.

8. A two part blank for forming a cushioned receptacle, said two part blank comprising a first blank part embodying a plurality of aligned successive panels defined and separated from each other by score lines, a terminal one of said panels being of approximately half the width of the other panels and having at least two longitudinally directed locking tongues bordering the longitudinal edge thereof, the said other panels being designed for forming an outer tubular receptacle shell, the said other panels having end flaps for forming closures for the ends of the outer shell, a second blank part embodying a plurality of aligned successive panels defined and separated from each other by score lines, a terminal one of the panels of the second blank part being of approximately half the width of the other of said second blank part panels and having at least two longitudinally extending locking tongues bordering the longitudinal edge thereof, the tongues of the two half-width panels being formed for interlocking connection to couple the two blank parts together, that panel of the second blank part which joins the half-panel thereof being of greater width than the remaining panels of the second blank part, the said remaining panels of the second blank part being of materially less width than the said other panels of the first blank part, said remaining panels and the said panel of greater width together forming an inner tubular receptacle shell spaced from the said outer receptacle shell when the coupled together blank parts are folded to form the receptacle, and certain of the panels of the second blank part being cut out along the score lines separating the same to form oppositely facing projections on the tubular inner shell of a width to span the space between the formed tubular inner and outer shells to maintain the shells in spaced relation.

9. The invention according to claim 8, wherein all the panels of the first blank part and the panels of the second blank part have bottom edges in substantial alignment when the two blank parts are coupled together and the said other panels of the second blank part are less length than the said other panels of the first blank part and have their top edges in a line in parallel offset relation with the top edges of both of the half-panels of the said other panels of the first blank part.
